SHUTTLECOCK

Irving Lawner, East Rockaway, and Joseph Lipman, Kew Gardens, N. Y.

Application March 27, 1953, Serial No. 24,223

Term of patent 14 years

(Cl. D34—5)

To all whom it may concern:

Be it known that we, Irving Lawner and Joseph Lipman, citizens of the United States of America, and residents, respectively, of East Rockaway, Nassau County, New York, and Kew Gardens, Queens County, New York, have invented a new, original, and ornamental Design for a Shuttlecock, of which the following is a specification, reference being had to the accompanying drawing forming part thereof.

Fig. 1 is an isometric view of a shuttlecock showing our new design.

Fig. 2 is a side elevation of the new design, a

portion thereof on the vertical center line being broken away to exhibit the interior.

We claim:

The ornamental design for a shuttlecock, substantially as shown and described.

IRVING LAWNER.
JOSEPH LIPMAN.
